AUTOMOBILE

Arthur Ross, Detroit, Mich., assignor to General Motors Corporation, Detroit, Mich., a corporation of Delaware

Application October 25, 1956, Serial No. 43,513

Term of patent 7 years

(Cl. D14—3)

Figure 1 is a side elevational view of an automobile showing my new design;

Figure 2 is a front elevational view thereof; and

Figure 3 is a top plan view thereof.

The dominant features of my design reside in the full line portions of the drawings.

I claim:

The ornamental design for an automobile, substantially as shown and described.
